DESIGN FOR A LAMP FIXTURE

Robert A. Clark, Jr., Chicago, Ill.

Application November 5, 1945, Serial No. 123,456

Term of patent 3½ years

(Cl. D48—23)

To all whom it may concern:

Be it known that I, Robert A. Clark, Jr., a citizen of the United States, residing at Chicago, in the county of Cook and State of Illinois, have invented a new, original, and ornamental Design for a Lamp Fixture, of which the following is a specification, reference being had to the accompanying drawing, forming part thereof, in which:

Fig. 1 is a perspective view of a lamp fixture embodying my new design; and

Figs. 2 and 3 are bottom-plan and end views respectively of the lamp fixture shown in Fig. 1.

I claim:

The ornamental design for a lamp fixture, substantially as shown.

ROBERT A. CLARK, JR.
